The dominant features of my design reside in those portions thereof shown in solid lines.

I claim:

The ornamental design for a snow blower, as shown and described.
